ROCKET SPRING RAMP

Lafayette B. Hedge, Washington, D. C., assignor
to the United States of America as represented
by the Secretary of the Army

Application April 4, 1952, Serial No. 280,633

4 Claims. (Cl. 102—49)

(Granted under Title 35, U. S. Code (1952),
sec. 266)

1

The invention described herein may be manufactured and used by or for the Government for governmental purposes without the payment of any royalty thereon.

This invention relates to rockets and more particularly to a novel safety device that will greatly facilitate the handling and using of rocket projectiles under battle conditions.

For the sake of safety in handling such projectiles and also to prevent premature explosion thereof in a launching tube a locking device is furnished which is itself retained by a detent and a definite predetermined procedure must be followed before the projectile is in a condition to detonate.

In the "bazooka" type of rocket projectiles the locking device is a bore riding pin and the detent is a locking band, which band embraces the rocket body and maintains the bore riding pin in a depressed position. When the user removes the band preparatory to firing the bore riding pin is spring urged outwardly a short distance and it is held in this position by internal locks. It has been found that under battle conditions and especially at night the now protruding pin is likely to engage the edge of the launching tube and thereby prevent the user from thrusting it into the full launching position.

According to the present invention I avoid the above mentioned difficulty by providing a spring ramp that conveniently bridges the spacing between the rocket nose and the bore riding pin head whereby the pin is guided easily into the tube.

An embodiment of the invention is shown in the accompanying drawing in which:

Figure 1 is a fragmentary elevation of a rocket and launcher tube illustrating my invention.

Figure 2 is a view taken on lines 2—2 of Figure 1 and looking in the direction of the arrows.

Figure 3 is a view taken on lines 3—3 of Figure 1 and looking in the direction of the arrows.

Referring first to Figure 1, reference character 1 denotes the main body of the fuse provided with the usual threaded opening in its base adapted to be screwed into the main body of a rocket 2. A shaft 3 is slidably fitted within a longitudinal bore in the fuse body and carries a mushroom head 4 in the usual manner. Bore riding pin 6 is slidably engaged within a transverse cavity and bears a cap 7 which is normally engaged by the safety band (not shown) and which engages the interior of the launching tube during rocket travel therethrough. A spring ramp is shown in dotted lines in the position it

2

would normally assume when the locking band is in position, and in solid lines when the band is removed and the projectile is ready for insertion into the launching tube. The spring ram comprises a main leaf 9 and a branch leaf 10 suitably secured thereto. The spring ram bridges respectively the bore riding pin cap 7 with the mushroom head 4 and the shaft 3 substantially as shown. The leaves are made of relatively thin gauge spring steel so that they will be somewhat resilient in use. Branch leaf 10 is bifurcated as can be best seen in Figure 3 to straddle the shaft and engage piston 4 when the band is in place as is shown in the dotted lines. The main leaf 15 is turned back upon itself to form a hook 11 at one end for engagement with the outer face of mushroom head 4 and a flat 8 to bear against the top of cap 7.

A fragment of launcher tube body 13 having the usual outwardly flaring bell 14 is shown in a position to receive the fuse furnished with my novel spring ramp. As mentioned above the position of the bore riding pin with the locking band removed is illustrated in solid lines and it can be readily seen that when the fuse is inserted into the tube the interior of the bell 14 will engage main leaf 9 and smoothly guide the bore riding pin to its proper position within the tube.

I have described a preferred embodiment of my present invention and do not wish to be limited by the specific example here shown but only by the scope of the following claims.

I claim:

1. In combination with a rocket having a fuse adapted to be launched from a tube and including a bore riding pin, a spring ramp comprising a resilient main leaf including a reentrant portion at one end thereof forming a hook and a bent portion at the other end forming a flat engaging the said bore riding pin, the said hook bearing against a forward portion of said fuse and forming a bridge, and a bifurcated branch leaf secured to the said main leaf and depending therefrom to straddle a second forward portion of the said fuse to prevent lateral displacement of the spring ramp.

2. In combination with a rocket having a fuse adapted to be launched from a tube and including a bore riding pin, a spring ramp comprising a resilient main leaf having one end thereof forming a hook and the other end forming a flat engaging the said bore riding pin, a mushroom head at the forward portion of said fuse, the said hook extending forward and bearing against said mushroom head to form a bridge, a shaft slidably

in the said fuse and supporting the said mushroom head, a bifurcated branch leaf secured to the said main leaf and forming an acute angle therewith to extend toward and straddle said shaft.

3. In a fuse having a body and intended for use with rockets, a bore riding pin slidably in said body and adapted to be ejected during flight, a spring ramp comprising a resilient main leaf having one end thereof forming a hook and the other end forming a flat and engaging the said bore riding pin, a mushroom head at the forward portion of said fuse, the said hook extending forward and bearing against said mushroom head to form a bridge, a shaft slidably in the forward part of said body and supporting said head, a branch leaf bifurcated at one end thereof and straddling the said shaft and joined at the other end thereof to the said main leaf substantially midway between the said hook and the said flat. 20

4. In a combination with a rocket having a fuse adapted to be launched from a tube and including a bore riding pin, a spring member comprising

ing a resilient main leaf and a bifurcated branch leaf attached thereto to form a Y, said main leaf having one end thereof bent to form a hook and the other end bent to form a flat, a shaft having an enlarged head portion extending from the forward portion of said fuse, the said hook bearing against the said head portion and the said flat engaging the said bore riding pin to form a bridge, the said bifurcated branch leaf straddling the said shaft to prevent lateral motion of said spring member. 10
